Primary Examiner — T. Chase Nelson*Assistant Examiner* — Mark Cavanna(74) *Attorney, Agent, or Firm* — Seed IP Law Group PLLC(57) **CLAIM**

The ornamental design for a biomedical multifunction tester, as shown and described.

DESCRIPTION

FIG. 1 is a front elevation view of a biomedical multifunction tester showing my new design;

FIG. 2 is a top plan view thereof;

FIG. 3 is a bottom plan view thereof;

FIG. 4 is a rear elevation view thereof;

FIG. 5 is a left side elevation view thereof;

FIG. 6 is a right side elevation view thereof;

FIG. 7 is an upper front left perspective view thereof;

FIG. 8 is an upper front right perspective view thereof;

FIG. 9 is a lower front left perspective view thereof; and,

FIG. 10 is a lower front right perspective view thereof.

The broken lines shown in the figures illustrate environmental subject matter and form no part of the claimed design.
